UNITED STATES PATENT OFFICE.

ROBERT McHARDY, OF TORONTO, ONTARIO, CANADA.

OPENER FOR MILK-BOTTLES AND THE LIKE.

1,368,406.

Specification of Letters Patent. Patented Feb. 15, 1921.

Application filed December 6, 1919. Serial No. 343,017.

To all whom it may concern:

Be it known that I, ROBERT McHARDY, of the city of Toronto, in the county of York, in the Province of Ontario, Canada, have 5 invented certain new and useful Improvements in Openers for Milk-Bottles, and the like, of which the following is the specification.

My invention relates to improvements in 10 openers for milk bottles and the like and the object of the invention is to devise an instrument for removing the cardboard stoppers of these bottles so as to prevent the splashing over and spilling of the contents; a further object is to provide means 15 for retaining the removed stopper on the instrument and out of contact with the table; a still further object is to make the opener in such form that when lying on a table or 20 other flat surface neither will be damaged.

My invention consists of the arrangement of parts all as more fully described and illustrated in the accompanying drawings in which—

25 Figure 1 is a perspective view showing the manner in which my instrument is used.

Fig. 2 represents a fragmentary perspective view showing the manner in which my opener engages the stopper of a milk bottle.

30 Fig. 3 represents the opener resting in an inverted position with a removed stopper held thereby.

Fig. 4 represents the opener resting face downward on a flat surface.

35 Like characters of reference indicate corresponding parts in the different views.

1 indicates my opener comprising a loop 1^x, a straight shank portion 2, humps or upwardly disposed angular portions 3, a 40 straight shank portion 4, and depending spicular portions 5. 6 indicates a milk bottle. 7 indicates the groove near the top of the bottle in which fits the stopper 8 according to the usual practice.

45 My opener is constructed from a simple piece of wire in the following manner:—

The wire is bent about its center and the two free ends are twisted about themselves. This forms the loop or handle portion 50 proper and the straight shank portion 2. The two loose ends are now bent upwardly, then downwardly, forming humps or upwardly disposed angular portions 3, which are spaced apart. Next the loose ends are 55 again twisted about themselves forming the second straight shank portion 4. The free

ends extend in V-shaped formation from the portion 4 and terminate in the two depending spicular portions 5 which incline slightly inward. The shank portion 2 lies in the 60 plane of the loop 1^x. The humps 3 and shank portion 4 are so arranged that the latter is offset upwardly from plane of portions 1 and 2 in such a manner that the spicular portions 5 do not intercept this 65 plane.

The method of using my opener is illustrated in Fig. 1, and is as follows:—

The spicular portions 5 are placed on the stopper near the edge thereof and an outward pull is exerted, which causes the points to penetrate into the stopper. The stopper may then be readily withdrawn from the bottle. After withdrawal the stopper remains held by the spicular portions and the 75 thick cream which usually covers the bottom of the stopper can be wiped off on the edge of the bottle and thus saved. By laying the opener in an inverted position on the table the humps 3 hold the spicular portions raised from the table or other support so that the stopper is held out of contact with anything liable to contaminate it while it is removed from the bottle and also ready to be replaced in the bottle when necessary 80 without being touched by the fingers.

When the opener is laid face downward on a table or other flat surface it rests only on the loop 1^x and the portion 2 and no other parts of the instrument are in contact 90 with the surface. Owing to the relative arrangement of the various portions and in particular to the portion 4 being offset upwardly from the portions 1^x and 2, the points of the spicular portions 5 do not touch the 95 surface upon or against which the instrument is resting and therefore neither the points nor the surface can be damaged.

Hitherto the method of removing stoppers of this type has been to insert an instrument between the stopper and the bottle and pry the stopper up or to pierce the stopper with a sharp skewer-like instrument which usually results in forcing the stopper partially down into the bottle and splashing the 105 contents over the top thereof. By the use of my instrument this difficulty is entirely overcome as the groove 7 forms a bearing against which the edge of the stopper is pressed by the opener and there is no tendency to force 110 the stopper down into the bottle.

Another advantage of my device is the

provision for holding the removed stopper so as to allow of the cream on the bottom being readily wiped off on the bottle edge and saved and further when the instrument 5 is laid on the table the soiled stopper is kept out of contact with the table.

By making the instrument of such form that the spicular projections are supported clear of the supporting surface, whether 10 lying face downward or in the inverted position, the points of the opener are preserved in good condition and also there is no danger of marring the surface of a wall or table against which the instrument may be resting.

What I claim as my invention is:—

A wire bottle opener comprising a looped portion forming a handle, upwardly and downwardly extending portions forming a supporting member in conjunction with the end of the handle, a shank extending from 20 the supporting member in parallelism with the handle, portions of the wire diverging from the shank, and depending spicular members extending from the diverging portions, said spicular members terminating 25 above the plane of the handle for a purpose specified.

ROBERT McHARDY.
